(57) **CLAIM**

We claim the ornamental design for mounting arm for electronic display, as shown.

DESCRIPTION

FIG. 1 is a perspective view of a mounting arm for electronic display according to the invention;

FIG. 2 is a side elevation view of a mounting arm for electronic display according to the invention;

FIG. 3 is an elevation view of a side of a mounting arm for electronic display opposing the side depicted in FIG. 2, according to the invention;

FIG. 4 is a bottom plan view of a mounting arm for electronic display according to the invention;

FIG. 5 is a top plan view of a mounting arm for electronic display according to the invention; and,

FIG. 6 is a third side elevation view of a mounting arm for electronic display according to the invention.
